ATTORNEY'S.

UNITED STATES PATENT OFFICE.

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND.

WINDOW FRAME AND SASH CONSTRUCTION.

Application filed April 23, 1926. Serial No. 104,086.

The present invention relates to windows of the type having openings through the inner wall of the jamb, plates extending through such openings; and in which the functional relations between the sashes and the jambs take place behind the inner wall of the jamb.

I aim to provide a window which can be made relatively cheaply and which will be particularly weather-tight. I accomplish this result by having chain lugs extending out from the sash plate, which lugs extend through second openings, through a partition in the jamb, either into the chain pockets or into inner chambers as may be desired. The chain lugs are so arranged that the lug for the lower sash is approximately at the bottom of that sash, and the lug for the upper sash is near the top. The openings through which these lugs pass do not extend the entire height of the sash. The one for the lower sash lug extends up only for the bottom half of the jamb height, whereas the opening for the upper chain lug extends down for the upper half of the sash height. A limitation of lateral movement of the sash can be taken care of by bending a portion of the sash plate at a right angle so that it will rub either against the rear of the inner jamb wall or against either the inner or outer face of the partition formed within the jamb. As is now usual with windows of this type, means is provided for preventing a direct passage of air back of the inner jamb wall from one opening in the jamb face to the other opening. Since the sashes have meeting rails which overlap each other at the middle of the window, when in closed position, the lower sash will extend up somewhat above the top of the opening for the lower sash chain lug, and in the same way the upper sash will go below the upper opening.

By building my window in this way, the opening below the upper sash and above the lower sash is completely closed when the window is closed, and there is no chance for any substantial leakage from one of these openings to the other, as for example, through the holes for the sash chains. At the same time, if any cold air leaks in around the outer seal of either of the sashes, this will not build up an immediate pressure to force cold air into the room, but will be

cushioned not only by any space that may be provided between the inner jamb wall and the partition in the jamb, but also will be cushioned due to the fact that such air can pass back of the partition into the relatively large chamber in which the weights move. Because of this arrangement, I can greatly reduce or substantially eliminate the free space between the inner jamb wall and the partition within the jamb.

For the purposes of illustration, a window embodying my present invention is shown in the accompanying drawings, in which Fig. 1 is a section through a jamb taken on line 1-1 of Fig. 3; Fig. 2 is a similar section on line 2-2 of Fig. 3; Fig. 3 is a face view of one jamb, the sashes, sill and lintel being shown in section; Fig. 4 is a view of one side of the window from inside of the room with certain parts broken away; Fig. 5 is a sectional view through one of the jambs on line 5-5 of Fig. 3; and this figure also shows a detail of sill construction as it appears before the jamb is added to the sill; Fig. 6 is a sectional view through the sill with a connecting casting in place showing a portion of the drainage arrangement; Fig. 7 is an enlarged view (turned sideways) of the face of the jamb at the middle of the window; Fig. 8 is a sectional view of the parts illustrated in Fig. 7; Fig. 9 is a detailed face view of a filler block used in the middle of the jamb; Fig. 10 is a side view of the block illustrated in Fig. 9; Fig. 11 is a sectional view looking upward through one of the jambs; Fig. 12 is a sectional view of the upper part of one of the jambs on line 12-12 of Fig. 11; and Figs. 13 and 14 are detail views of certain portions of the sash construction.

In these drawings 20 is the usual cover for the weight box, provided with a hook 22 at the inner face. A staff bead 24 may be made of heavier metal than the cover 20 and attached to it as by welding, or the members 20 and 24 may be made of a single piece of metal. The member 24 has a portion 26 which forms a part of the inner face of the jamb and a part 28 bent inwardly to form a sash guide. The angle between the portions 26 and 28 preferably is slightly more than a right angle, so that only an edge of portion 28 will press against the jamb plate. A cover plate 30 is provided

which is adapted to engage with a hook 22 and has an inwardly bent portion 32 corresponding to similar portion 28.

In order to form a parting strip between the sashes, I provide two members 34 and 36 which are preferably identical in size and shape, but are inserted in reverse position. Each of these members is of a length equal to substantially half the height of the jamb and is of an approximate Z-shape, with the middle connecting bar of the Z forming an angle of slightly less than 90° with each of the adjacent portions. Members 34 and 36 may, if desired, be hot rolled sections, or they can be bent from metal plates. Member 34, which is the lower of these two members, is attached, as by screws 38, to portion 26 of bead 24 and runs up from a connecting casting located near the sill (which will be described hereafter) to the point where its upper edge is in a position just to be cleared by the lower edge of the upper sash when the upper sash is fully raised (see Fig. 3). Member 36 is attached in the reverse but corresponding position to cover plate 30 and runs from the bottom face of the lintel down to the point where its lower edge meets the upper edge of member 34. The exposed joint of these two members may be covered by a rubbing block 40.

The lower sash 42 is provided with a plate 44 which, when the window is closed, lies between an edge of member 34 and portion 32 of cover plate 30. Near the bottom corner of this sash (see Fig. 13) I provide a chain lug 46 which may be welded to plate 44 by the use of a dovetailed joint as indicated in dotted lines in Fig. 13. Riveted to one face of chain lug 46 is an angle iron 48 which is adapted to run against the rear face of cover plate 30 (see Fig. 2) to limit transverse movement of the lower portion of the lower sash. Member 48 is preferably bent so that the angle between the two legs is slightly greater than a right angle. Since plate 44 extends up above member 34 even when the window is closed, the upper edge of this plate will always be opposite a portion of member 36. In order to insure a close connection between these members, a slot is cut in the top of plate 44 and a portion 50 is bent out just far enough to rub against member 36. The upper sash 52 is provided with a plate 54, a chain lug 56 located near the top of the sash, and an angle iron 58 (corresponding to the angle iron 48 of the lower sash) which is adapted to rub against the inner face of portion 26 of bead 24. It also has, at its lower edge, a bent-out portion 60 (corresponding to the portion 50 on the upper edge of the lower sash) which makes contact with member 34.

It may be noted from Fig. 2 that when the window is closed, plate 54 of upper sash 52 extends down only to the top of member

34, and does not overlap this member in the same way that the upper edge of plate 44 overlaps the lower portion of member 36. As a substitute for such overlapping, and at the same time to assist in making the window tight, I provide a special casting 62 which is illustrated in Figs. 7, 8, 9 and 10 and the general position of which is shown in Fig. 3. This casting is held in place immediately above the upper edge of member 34 by a tie-plate 64 which is connected to both cover plate 30 and portion 26 of bead 24. (The tie-plate 64 might be shown in Fig. 2 but is there omitted for the sake of clarity.) Casting 62 has a main base portion 66 of the same thickness as members 34 and 36 so that its inner face will be a direct continuation of the inner face of member 34 and will serve to guide the bent-out portion 60 of upper sash 52 onto the inner face of member 34. Toward the outside of the window, casting 62 has a portion 68 adapted to fill the angle of curvature formed when portion 28 is bent inwardly from bead 24. It also has a portion 70 which extends up and meets the rear face of member 36. When the upper sash is closed, plate 54 (including bent portion 60) will entirely fill the slot formed between portion 70 of casting 62 and the edge of member 36, on one hand, and between portion 68 of casting 62 and portion 28 of bead 24 on the other hand; and thus the upward leakage of cold air around the sides of plate 54 will be prevented.

Casting 62 also serves a highly useful function in assembling and disassembling the window. If the window is assembled and it is desired to remove the sashes, cover plate 30 is first taken off and the lower sash swung inwardly. Member 36 is removed, and then screw 65 is taken out, which permits casting 62 to be swung inwardly along with the upper sash, without disturbing member 34. Thus the clearance between member 34 and portion 28 of bead 24 can be accurately determined and fixed in the factory. The clearance between cover plate 30 and member 36 can be adjusted in the field owing to the fact that the openings through cover plate 30 for the screws which hold these members together, are slightly enlarged. The openings for the screws which hold casting 62 to tie-plate 64 are also preferably made large enough to provide for some adjustment.

The sill 71 which is of the general shape shown in a number of my earlier patents, has a ridge 72 inside of which is a valley 74. Inside of the line of the face of each jamb, a groove 76 is formed through the ridge 72 so that the valley 74 may drain outward. The jambs are connected to the sills by the use of a casting 78 illustrated in Figs. 5 and 6. This casting covers groove

76 and has a portion 80 which extends down into the valley 74, but does not completely fill this valley. The casting 78 likewise has a main base portion 82 which lies on top of the upper portion of the sill 71 and from which extends upwardly a lug 84 to which cover plate 30 is attached. At the back of the casting 78 there is a raised flange 86 which continues around the side at 88 and serves as a point of attachment for the cover 20. The base portion 82 is extended inwardly as shown at 90 in Fig. 5 so that it will underlie portion 32 of cover plate 30. A flange 91 connects the main base portion 82 to the portion 92 which serves as a base for member 34. This portion 92 extends towards the outside of the window far enough to contact with portion 28 of bead 24 and is shaped to fill the angle of curvature formed when this portion is bent inwardly. A bolt 96 passes through flange 91 and is held in place by lock nut 98. This bolt in turn passes through the lower portion of member 34 and by the aid of lock nuts 100, member 34 can either be moved back, or held in, as desired. In order to take care of any water that may get into the inside of the box 20, a small weep-hole 102 is provided in the lower corner of bead 24.

The connection between the lintel 104 and the jamb face members is primarily accomplished by the aid of an angle iron 106 (see Figs. 11 and 12) to which the upper portion 35 of member 36 is attached by a bolt and lock nuts, in the same way that lower portion of member 34 is attached to lug 84 of casting 78. The pulleys 108 are hung from the underside of angle iron 106.

40 There are certain features about this window that deserve particular note. When the sashes are in a closed position, there is no opening above the lower sash which leads from the inside of the room either into the chain pocket or into any portion of the jamb which is accessible to outside air. It further may be noted that this window is so designed that when it is subjected to heavy air pressure, as in a gale, the pressure will tend to tighten the window. Ordinarily in windows of the type having concealed chains and plates extending through openings in the inner wall of the jamb, outside air pressure will tend to force the lower sash inwardly, permitting cold air to enter the chain pocket of the lower sash and rise through the relatively large openings afforded by the chain pocket and come into the room through the opening above the lower sash. In the present arrangement, air pressure from the outside can force its way into the jamb by pushing the lower sash in slightly, but there is practically no opening for the air to pass upwardly around the edge of the lower sash into the opening

above the lower sash, and the harder the wind blows, the more the lower sash will press against portion 32 and cover-plate 30, to prevent the air from entering the room. It will also be noted that when the window is closed, relatively large compression chambers are formed for both the upper and lower sashes, as any air which forces its way past the outside seals of these sashes, will enter the jamb and chain pocket. This feature is of particular importance in connection with preventing any water from being forced into the room, for any water that is carried past the outside seals will drop out of the air due to the fact that the velocity will drop in the large compression chamber. This water will run down inside the jamb, and will be forced out through weep-hole 102, at any time that the air pressure momentarily drops. In other words, I have a window which is relatively cheap to manufacture, is carefully designed so as to be relatively air-tight and which contains particular provision to prevent any water from being forced in; at the same time the window is very easy to operate.

It is to be understood that the foregoing details are given by way of illustration only and that they may be modified in many particulars without departing from the spirit of my invention.

Certain of the features of this window which are claimed broadly in this application were disclosed in my earlier application, Serial No. 83,999, filed January 27, 1926, 100 but are not now claimed therein.

What I claim is:

1. A window-frame and sash construction of the type in which the sash chains are behind the inner faces of the jambs and in which the sashes are provided with plates extending into openings in the inner face of the jamb, comprising jambs having an opening for a lower sash which is entirely closed, above the middle of the window, against the passage of air into a weight chamber or into any inner part of the jamb which may connect with the corresponding opening for the upper sash, and having an opening for an upper sash which is entirely closed, below the middle of the window, against the passage of air into any inner part of the jamb which may connect with the corresponding opening for the lower sash. 110

2. A window-frame and sash construction comprising a jamb having two vertical openings between members forming the inner face of the jamb, respectively adapted to receive a lower and an upper sash, a partition in the jamb behind the opening for the lower sash running down from the top of the jamb to about the middle thereof, an opening below such partition leading back thereof, upper and lower sashes adapted to 120

- 4 move in said first-mentioned openings, a projecting member adjacent the bottom of the lower sash adapted to extend into the jamb beyond said partition and suspension mechanism attached to said projecting member.
3. A device as specified in claim 2, further characterized by having a partition back of the opening for the upper sash which extends up from the bottom of the jamb to about the middle thereof, and by having a suspension portion adjacent the top of the upper sash.
4. A device as defined in claim 2, further characterized by the fact that the sash plates include portions adapted to contact with jamb members back of the inner face of the jamb to limit transverse movement of the sashes.
5. A window-frame and sash construction comprising jambs, an upper and lower sash adapted to move in the jambs, suspension mechanism comprising pulley wheels within the jambs, and partitions within the jambs between the room side of the upper half of the jamb and the pulley wheels for the lower sash.
6. A construction as specified in claim 5 further characterized by having enlarged compression chambers which are adjacent the sides of the lower sash when the lower sash is in closed position.
7. A window-frame and sash construction comprising jambs, two openings between the members forming the inner wall of each jamb, sashes having plates extending through said openings, a chamber and channels within each jamb and connecting pas-
- 5 sages and partitions so arranged that the lower portion of the opening for the lower sash leads into an enlarged compression chamber while the upper part leads into a relatively smaller channel and the upper part of the opening for the upper sash leads into an enlarged compression chamber while the lower part leads into a relatively smaller channel.
8. A window-frame and sash construction comprising two jambs each comprising two side members and an upper and lower parting strip member with openings between the side members and parting strip members to receive the sashes, the upper parting strip member serving to form a partition back of the upper portion of the opening for the lower sash and the lower parting strip member serving to form a partition back of the lower portion of the opening for the upper sash, and upper and lower sashes adapted to move in said openings.
9. A construction as specified in claim 8, in which the lower parting strip member does not overlap the upper sash when the upper sash is raised, and an auxiliary member removable without removing the lower parting strip member is positioned above the partition portion of the lower parting strip member and serves as a continuation of such partition.
10. A window-frame construction comprising two jambs, a sill having a ridge and a valley behind said ridge extending back of the face of the jambs, and an opening through the ridge back of each jamb face to permit water to drain out of the valley.

HARRY E. CAMPBELL.
